GUSTAVE A. CARLSON, OF DETROIT, MICHIGAN

GRINDING AND POLISHING MACHINE

Application filed June 20, 1920. Serial No. 462,465.

The present invention pertains to a novel grinding and polishing machine of a type particularly adapted for grinding and polishing the shells of head lights used upon automobile and similar vehicles.

The primary object of the present invention is to devise a machine for supporting and rotating a headlight shell in contact with a grinding or polishing wheel, the machine being capable of adapting itself to accommodate both semi-spherical and parabolic shells. The shell is supported adjacent the grinding or polishing wheel to contact therewith and is rotated upon both a horizontal and vertical axis while it is being moved longitudinally in a horizontal plane, thereby permitting the use of a comparatively wide grinding and polishing wheel and insuring even wear upon the latter due to the manner in which the shell is moved along the horizontal plane. Mechanism is provided to insure even grinding of the shell and for swinging the work supporting members a sufficient distance away from the wheel that the work may be conveniently removed from its supporting chuck without danger of it contacting with the wheel during the removing operation.

With the above and other ends in view the invention consists in the matters hereinafter set forth and more particularly pointed out in the appended claims, reference being had to the accompanying drawings, in which

Figure 1 is a side elevation of the present machine during the grinding operation;

Fig. 2 is a fragmentary cross sectional view of the machine, taken on the line 2-2 of Fig. 1;

Fig. 3 is a front elevation of the machine, partly broken away and in cross section;

Fig. 4 is a cross sectional view taken on the line 4-4 of Fig. 3, and

Fig. 5 is a top plan view.

Like characters of reference are employed throughout to designate the corresponding parts.

The numeral 1 indicates a grinding wheel which is mounted upon a base 2 and driven by any suitable means.

A base member 3 is formed with a head 4 in which are formed ways 5 to receive the

table 6, a hand wheel 7 being mounted upon a screw 8 to propel the table 6 longitudinally in the ways 5. In the upper surface of the table 6 and at right angles to the ways 5 there are provided ways 9 which receive the cross table 10, a hand wheel 11 being mounted upon a screw 12 for moving the table in the ways 9.

The cross table 10 is provided with a central bore to accommodate a bolt 13 which secures a plate 14 upon the upper surface of the table in a manner permitting rotative movement of the plate relative thereto. A bracket 15 is bolted to the upper surface of the plate 14 as at 16 and pivotally supports a lever 17 which has its inner end forked as at 18 to receive a pintle 19 mounted in a pin 20. The pin 20 projects through a bore 21 in the plate 14 and the lower projecting end is received in a hole 22 in the upper surface of the table 10 in a manner to prevent rotation of the plate relative to the table. A coiled spring 23 exerts pressure upon the lever 17 whereby it maintains the pin 20 in the hole 22 and by moving the lever 17 in a manner to compress the spring 23 the pin 20 is withdrawn from the hole 22 and rotation of the plate relative to the table 10 is permitted.

On the upper surface of the plate 14 are formed ears 24 to which are pivotally secured the ears 25 that are formed on the under surface of guide plate 26. Compressed coiled springs 27 are interposed between the plate 14 and the guide plate 26 to exert upward pressure on the latter and a set screw 28 is rigidly secured in the plate 14 by nuts 29 and projects upwardly through and above the guide plate and has a spring surrounding the upper portion thereof and adapted to exert pressure downwardly upon the guide plate 26 when compressed by means of the wing nut 30. A positioning screw 31 has its lower end secured in the plate 14 by nuts 32 and has its upper end projecting through the guide plate 26 so that by tightening the nuts 33 against both sides of the guide plate pivotal movement thereof can be prevented and by spacing the nuts as illustrated in the drawings they provide positive limits for the pivotal movement of the guide plate.

The guide plate 26 supports a carriage 34 in a manner to guide it in longitudinal movement, the carriage having a boss 35 formed thereof to receive the lower end of a shaft 36 which projects upwardly through the casing 37 into the casing 38 to which it is keyed as at 39. Beneath the casing 37 there is keyed on the shaft 36 a pinion 40 which meshes with the rack 41 that is mounted by a bracket 42 upon the guide plate 26 and it therefore becomes apparent that sliding movement of the carriage causes rotation of the shaft 36 and the casing 38 which is keyed thereto.

Supported by a bracket 43 upon the upper part of the casing 38 is a motor 44 having a belt 45 to drive the wheel or pulley 46 to rotate a worm 47. The worm 47 rotates a worm wheel that is mounted upon a shaft 49 which is journalled at both ends in the casing 36. A worm 50 is mounted upon the shaft 49 to rotate a worm wheel 51 that is mounted upon the vertical shaft 52 which has its lower end supported in a frame 53 formed on the carriage 34. The lower end of the shaft 52 supports a crank arm 54 which has a slot 55 formed therein to receive a pintle 56 that supports the roller 56' that is received between a pair of cross members 57 that are rigidly mounted upon the guide plate 26. It is apparent from this description that rotation of the crank 54 causes the carriage 34 to slide back and forth on the guide plate 26.

On the outer extremity of the shaft 67 is formed a head 68 which is slotted to pivotally support a plurality of bell-crank levers 69 that are normally forced outwardly by springs 70. The head 68 is provided with shoulders 71 to engage the outside of a flange formed on the head-light shell 72 while the bell crank levers engage the inside of the flange to hold the shell on the head 68. To operate the bell crank levers in a manner to draw them into contact with the shell there is provided brackets 73 on the casing 38 to support a lever 74 which slides the adjusting member 76 in a manner whereby the recess 75 formed in the end thereof engages the bell crank levers to rock the same on their pivots.

When the shell 72 has been placed on the head 68 in the above described manner the shell is brought into contact with the wheel by manipulation of the hand wheels 7 and 11. The motor 44 then drives the shaft 49 and the worm 50 rotates the wheel 51 to rotate the crank 54 which causes sliding movement back and forth of the carriage 34, causing the head 68 and the shell 72 to be moved across the face of the wheel 1. The sliding movement of the carriage causes the gear 40 to be moved correspondingly across the rack 41 which causes rotation of the shaft 36 according to the direction of the sliding movement and the casing 38, being keyed to the shaft 36 rotates therewith from the posi-

tion shown in full lines in Fig. 5 to that shown in phantom lines.

At the same time the above movement is taking place the motor is rotating the shaft 67 and head 68 through the shaft 49, gear 50, sleeve 60, gear 61, gear 62, shaft 63, pinion 64, idler gear 65 and gear 66 the shell may be conveniently ground.

It is obvious and well known that when sliding movement is caused by a rotating crank in the manner in which the carriage 34 is moved that when the carriage comes to the end of its sliding movement there is a slight hesitation before it starts back again. To prevent excess grinding of that portion of the shell which is in contact with the wheel when this hesitation occurs the present invention provides a member 76 having cams 77 formed or mounted upon each end thereof, the member 76 being rigidly secured upon the sliding carriage 34 and having the cams positioned so that they engage a roller 78 at precisely the moment the above described hesitation occurs. The roller 78 is supported by an arm 79 which is rigidly secured upon the plate 14 so that the cams 77 cause the carriage and guide plate 26 to move on its pivot to rock the head 68 and shell 72 out of contact with the grinding wheel 1.

When the work has been ground by its rotative reciprocation across the face of the wheel 1 the lever 17 is depressed, causing the pin 20 to be withdrawn from the hole 22 so that the entire mechanism may be rotated upon the bolt 13 to a position where the shell may be conveniently removed and replaced.

Although a specific embodiment of the present invention has been illustrated and described it is to be understood that various changes may be made in the details of construction without departing from the spirit of the invention as depicted in the following claims, and such changes are contemplated.

What I claim is:—

1. The combination with a grinding wheel, of a rotatable head adapted to support a shell, a casing supporting said head, longitudinally slidable means supporting said casing, a rack and pinion connection between said casing and said slidable means whereby sliding movement of said means causes rotation of said casing, and a motor for rotating said head and sliding said slidable means.

2. The combination with a grinding wheel, of a rotatable work supporting head, a casing supporting said head, a slidable carriage supporting said casing, a rack, a gear carried by said casing and engaging said rack in a manner whereby sliding movement of said carriage causes rotation of said casing, and a motor for rotating said head and sliding said carriage.

3. The combination with a grinding wheel,

- of a pivoted guide plate, a slidable carriage mounted upon said guide plate, a casing supported by said carriage, means for causing rotation of said casing as a result of the sliding movement of said carriage, a rotatable head supported by said casing and adapted to support a shell to be ground, and a motor for reciprocating said carriage and rotating said head.
- 10 4. The combination with a grinding wheel, of a pivoted guide plate, a slidable carriage mounted upon said guide plate, a casing supported by said carriage, means for causing rotation of said casing as a result of the sliding movement of said carriage, a rotatable head supported by said casing and adapted to support a shell to be ground, a motor for reciprocating said carriage and rotating said head, and resilient means for exerting pressure upon said pivoted guide plate whereby the shell on said head contacts with the grinding wheel at all stages of the rotation of said casing.
- 15 5. The combination with a grinding wheel, of an adjustable table, a pivoted guide plate supported upon said table, a reciprocal carriage mounted upon said guide plate, a casing carried by said carriage and having a gear secured thereto and meshing with a rack carried by said guide plate whereby reciprocation of said carriage causes rotation of said casing, a work supporting head supported by said casing, and a motor connected to drive said head and reciprocate said carriage.
- 20 6. The combination with a grinding wheel, of an adjustable table, a pivoted guide plate supported upon said table, a reciprocal carriage mounted upon said guide plate, a casing carried by said carriage and having a gear secured thereto and meshing with a rack carried by said guide plate whereby reciprocation of said carriage causes rotation of said casing, a work supporting head supported by said casing, a motor connected to drive said head and reciprocate said carriage, and resilient means acting upon said pivoted guide plate to hold the work on said head in contact with said wheel.
- 25 7. The combination with a grinding wheel, of an adjustable table, a pivoted guide plate supported upon said table, a reciprocal carriage mounted upon said guide plate, a casing carried by said carriage and having a gear secured thereto and meshing with a rack carried by said guide plate whereby reciprocation of said carriage causes rotation of said casing, a work supporting head supported by said casing, a motor connected to drive said head and reciprocate said carriage, resilient means acting upon said pivoted guide plate to hold the work on said head in contact with said wheel, cams mounted upon said reciprocal carriage, and a roller supported by

70 said roller engages said cams at the end of the reciprocable movement of said carriage to pivot said guide plate and move the work supporting head away from said grinding wheel.

In testimony whereof I affix my signature.
GUSTAVE A. CARLSON.
